UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING-MACHINE.

1,378,813.

Specification of Letters Patent. Patented May 17, 1921.

Application filed February 28, 1919. Serial No. 279,866.

To all whom it may concern:

Be it known that I, MORRIS P. HOLMES, a citizen of the United States, residing at Claremont, in the county of Sullivan and State of New Hampshire, have invented certain new and useful Improvements in Mining-Machines, of which the following is a full, clear, and exact specification.

My invention relates to mining machines.

10 It has for its object to provide an improved truck especially adapted to use in connection with mining machines, and more particularly an improved truck of the type having a tilting member whereon the mining machine may be loaded or unloaded from the truck. More specifically, my invention has for its object to provide an improved truck of the type set forth, having its tilting member pivotally connected 20 to the truck in an improved, simple, and rugged manner.

25 In the accompanying drawings I have shown for purposes of illustration one embodiment which my invention may assume in practice.

In these drawings.—

Figure 1 is a side elevation of my improved truck with a mining machine mounted in transport position thereon.

30 Fig. 2 is a side elevation of the truck with the mining machine shown in process of being loaded thereon.

Fig. 3 is a detail view showing my improved pivot for the tilting member.

35 In this illustrative construction, I have shown a self-propelled truck frame 1 of usual construction adapted to carry a mining machine and having rigid and continuous flanged side members and front and rear wheels, the truck frame herein being provided with a longitudinally flanged tilting member 2 upon which the mining machine travels in its movement onto or from the truck. Inasmuch as these various elements are broadly old, and my present invention is directed to the pivot and supporting means for this tilting member, a further description of the other mechanism seems to be unnecessary.

50 In my improved construction it will be observed that the tilting member 2 is pivotally supported in an improved manner at the front end of the truck frame 1. More particularly, it will be observed that an im-

proved, simplified, and rugged pivot is provided therefor. This means, as shown herein, is in the form of an upstanding transverse plate 3 fixed to and extending across the front end of the truck frame 1 and forming what may be called a knife edge pivot. As shown, this plate co-operates with a rear bottom plate 4 on the tilting member 2 to support the latter in its horizontal position upon the truck, and yet spaced from the upper horizontal surface thereof, the bottom plate then resting upon the bottom of the frame 1 and supporting the rear end of the member 2 while the front end of the latter is supported on the plate 3. It will also be noted that as the tilting member 2 is tilted from the position shown in Fig. 1 to the position shown in Fig. 2 during the discharge of the machine, and as the same is tilted from the position shown in Fig. 2 to the position shown in Fig. 1 during the loading of the machine, this member moves about the upper edge of the plate 3, as on a knife edge pivot, the member 2, as it approaches its extreme positions also having a limited sliding movement 80 relative to the edge of the plate 3. It will also be observed that attached to the member 2 and disposed beneath the same I have provided a keeper adapted to hold the member 2 in the desired operative relation to the plate 3 and co-operate with the latter during the sliding movement mentioned. This keeper herein assumes the shape of a lip or U-shaped member 5 having one arm fixed to the bottom of the member 3 and another shorter arm extending upward relative to a transversely disposed and depending portion 6 herein suitably formed by the lower end of the plate 3, although the depending portion 6, as illustrated, may 95 also include a co-operating transverse member 7 of angle construction fixed thereto and to the bottom of the frame 1 and co-operating with the plate 3 to provide an exceedingly rigid and rugged structure. 100

As a result of my improved construction, it will be noted that an exceedingly simple and rugged truck is provided which is adapted to be very cheaply manufactured. More particularly, it will be observed that the pivotal connection of the member 2 is exceptionally rugged and adapted to rough usage wear being minimized at the same

time that a construction is provided which is adapted to be very cheaply manufactured, all machining being unnecessary. It will also be observed that due to the slight sliding action of the tilting member 2 relative to the member 3, not only is the wear distributed over a relatively large surface, but a slight retarding action is obtained tending to prevent the tilting member from suddenly occupying either of its extreme positions when the weight of the machine is upon an extremity of the same. Further, it will be noted that by supporting the tilting member when in its horizontal position on two longitudinally spaced supports, comprising herein its pivot and the rearwardly located plate 4, space is provided between the bottom of the tilting member and the upper surface of the horizontal portion 20 of the truck frame 1 in such a manner as to permit the usual truck driving gear on the mining machine always to register in the desired relation with the coöperating gear on the truck despite accumulations of coal dust or the like which ordinarily accumulate adjacent the pivot of the tilting member and would otherwise limit the downward movement thereof. These and other advantages of my improved construction will, however, be clearly apparent to those skilled in the art.

While I have in this application specifically described one form which my invention may assume in practice, it is to be understood that the invention may be modified and embodied in various forms without departing from its spirit or the scope of the appended claims.

What I claim as new and desire to secure by Letters Patent is:

1. In combination, a truck frame, a transverse plate thereon, and a tilting member turning directly on said plate during its tilting operation.
2. In combination, a truck frame, means forming a transverse knife edge at the front thereof, and a tilting member turning on said knife edge during its tilting operation.
3. In combination, a truck frame, means forming a transverse bearing at the front end thereof, and a tilting machine supporting member slidable relative thereto during its tilting operation.
4. In combination, a truck frame, a transverse member thereon, a machine receiving member tiltable and slidable on said member, and means for operatively connecting said elements.
5. In combination, a truck frame, means forming a transverse knife edge bearing at the front end thereof, a tilting machine supporting member tiltable thereon during

its tilting operation, and means for maintaining said elements in operative relation.

6. In combination, a truck frame, means forming a transverse knife edge bearing at the front end thereof, a tilting machine supporting member tiltable thereon during its tilting operation, and means carried on the under side of said tilting member for maintaining said elements in operative relation. 70

7. In combination, a truck frame, an upstanding member extending transversely across the front of the same, a tilting member tiltable about the edge of said member as it moves to tilted position, and means for maintaining said tilting member in operative relation to said transverse member. 75

8. In combination, a truck frame, a transverse member thereon having a depending portion, a tilting machine supporting member tiltable thereon during its tilting operation, and a keeper carried by said tilting member and having a lip coöperating with said depending portion. 80

9. In a truck, a truck frame, means disposed transversely relative to its front end and forming a knife edge, a tilting member tiltable about said knife edge, and means coöperating with the said knife edge for supporting said tilting member in its horizontal position. 90

10. In a truck, a truck frame having front and rear supporting wheels, a tilting mining machine loading and unloading member pivoted at a point substantially midway between its ends on said frame and adjacent the front wheels of the latter on a transverse pivot disposed above the bottom of said frame, said member extending in rear 100 of the rear wheels, and means coöperating with said pivot to support the bottom of the portion of said tilting member in rear of its pivot above and in spaced relation to the upper surface of said truck frame. 105

11. In a truck, a truck frame having rigid and continuous flanged side members and front and rear supporting wheels, a longitudinally tilting flanged mining machine loading and unloading member pivoted at 110 a point substantially midway between its ends on said frame and adjacent the front wheels of the latter on a transverse pivot disposed above the bottom of said frame, said member extending in rear of the rear 115 wheels and being receivable between the flanged side members of the truck frame, and means coöperating with said pivot to support the bottom of the portion of said tilting member in rear of its pivot above 120 and in spaced relation to the upper surface of said truck frame.

In testimony whereof I affix my signature.
MORRIS P. HOLMES.
